UNITED STATES PATENT OFFICE.

DANIEL L. HUGHES, OF MILWAUKEE, WISCONSIN.

PAPER FOR BOILER-COVERING.

SPECIFICATION forming part of Letters Patent No. 299,983, dated June 10, 1884.

Application filed August 24, 1883. (No specimens.)

117-90

To all whom it may concern:

Be it known that I, DANIEL L. HUGHES, a citizen of the United States, residing at Milwaukee, in the county of Milwaukee and State 5 of Wisconsin, have invented certain new and useful Improvements in Paper for Boiler-Covering; and I do hereby declare the following to be a full, clear, and exact description of the invention, such as will enable others skilled 10 in the art to which it appertains to make and use the same, reference being had to the accompanying drawing, and to letters or figures of reference marked thereon, which form a part of this specification.

15 The accompanying drawing represents a cross-section of a steam-pipe surrounded with boiler-covering, the paper and cloth of which are prepared by my improved method.

Like parts in said drawing are represented 20 by the same reference-letters.

A represents a steam-pipe; B, a sheet-metal support for the covering. C C represent paper, and D cloth, prepared by my improved method. E represents a layer of felt or other 25 packing.

My invention relates particularly to the improvements in methods of treating paper and cloth whereby the same is made non-combustible, and is adapted to be used as a covering 30 for steam pipes and boilers. The cloth or paper is first thoroughly saturated with silicate

and allowed to dry, when it is coated with a paste formed as follows: black oxide of magnesia, two parts; zinc-white, two parts; silicate soda, about four parts, or sufficient in 35 quantity to reduce the magnesia and zinc-white to a thin paste-like consistency. To one gallon of the resulting compound add one part of linseed-oil. The compound thus formed having been spread upon the paper or cloth, 40 the same is allowed to become thoroughly dry, when it is again covered with a thin coating of silicate soda, when it is ready for use.

Having thus described my invention, what I claim as new, and desire to secure by Letters 45 Patent, is—

The method of making paper and cloth non-combustible for steam-pipes, consisting, first, in saturating the same with silicate; second, coating the same when dry with a compound 50 formed of black oxide of magnesia, two parts; zinc-white, two parts; silicate soda, four parts; linseed-oil, one part; and, third, coating the covering when dry with silicate soda, all substantially as set forth.

In testimony whereof I affix my signature in presence of two witnesses.

DANIEL L. HUGHES.
